UNITED STATES PATENT OFFICE.

JAMES CLIFFORD JOHNSON, OF MINNEAPOLIS, MINNESOTA.

SHOW CASE.

Application filed January 19, 1925. Serial No. 3,392.

The object of my invention is to provide a show or display case wherein such articles as shelled nuts of different kinds may be conveniently placed and attractively displayed to prospective customers.

A further object is to provide a case of the character described which not only will display in a pleasing manner the goods to be sold but will allow convenient access thereto for dispensing purposes.

A further object is to provide a case which will be clean and sanitary and easily accessible in all parts for cleansing purposes.

The invention consists generally in various constructions and combinations all as hereinafter described and particularly pointed out in the claims.

In the accompanying drawings forming part of this specification,

Figure 1 is a perspective view of a show-case embodying my invention;

Figure 2 is a vertical sectional view of the same;

Figure 3 is a perspective view of the rear of the case with the door or gate open showing the interior of the empty case;

Figure 4 is an enlarged detail view showing the locking means provided at the front corners of the case;

Figure 5 is a sectional view on the line 5-5 of Figure 4.

In the drawings, 2 represents a suitable base. This may be of any desired length according to the number of compartments in the case and is adapted to rest upon the floor or a suitable support such as a counter or table. 3 is a glass plate forming the front wall of the show-case; 4, similar end plates or panels, the lower edge of the front panel being held between a longitudinal moulding 5 and a rail 6 on the base, and the end panels or plates being supported in a similar manner and abutting a rear rail 7 at the bottom and a rail 8 at the top. The front and end plates are secured at the front of the case by angle braces 9 fitting the angles at the front as indicated in Figures 1 and 4. A longitudinal rail 10 extends along the rear of the show-case intermediate the top and bottom thereof and is rabbeted at 11 to receive the lower edge of a transparent plate 12, the upper edge of which fits a corresponding rabbet 13. The rear corners of the case have upright standards

or posts 14 between the rails 7, 8 and 10. The top of the case is closed by a plate 15, preferably transparent, and in the space between the rails 7 and 10, I provide a door 16 hinged at 17 and having a suitable spring catch 18 for holding it on its seat against the rail 10.

A floor 19 is provided in the case, the rear portion of which is adjacent an inclined surface 20 of the rail 7 and a series of vertical partitions 21, preferably of transparent material such as glass, fit within vertical grooves 22 in the rear rails 7 of the case and into transverse grooves 22a in the front rail 6. The top or cover 15 has its under surface close to the upper ends of these partitions forming close-fitting joints therewith, endwise movement of the top plate being prevented by means of the strips 23 mounted on the under side thereof and arranged to contact with the end walls or plates of the case.

Within the compartments so provided, and there may be any desired number of them according to the length of the case 80 and the desired capacity, I provide a series of, inclined plates 24 also preferably of transparent material such as glass having their lower ends resting upon the rail 6 and their upper ends upon the rail 10 adjacent 85 the lower edge of the plate 12; the inclination of these plates being preferably at an angle of about 45 degrees so that a triangular space is formed between each plate and the front wall of the case wherein the shelled nuts, candy, or other articles may be attractively displayed.

At the lower ends of the plates 24, the corners are cut away, providing gaps or openings 25 on each side communicating with the chambers or spaces 26 and through these openings the nuts or other material in the case will fall by gravity, as indicated in Figure 2, to a point where they may be conveniently reached by the clerk for sacking or dispensing purposes. The plates 24 are removable as well as the partitions separating the compartments so that it is a simple matter to remove them and thoroughly cleanse the interior of the case.

Means are also preferably provided for locking down the front edge of the top plate 15 in order to prevent an unauthorized person from raising the plate and reaching into the case. Such means preferably con-

sists in the provision of suitable hooks 28 secured to the strips 23 of the plate 15 and adapted to engage the lower edges of the angle braces 9 when the plate is closed, as shown in Figures 1 and 4. If desired, a means may also be provided for locking down the rear edge of the plate.

In making a sale, it is not necessary to open the top of the case and permit the entrance of air and dust or dirt into the cabinet, but by lowering the door at the rear, the lower interior will be exposed and the nuts or other material will be visible therein within convenient access of the salesman. The chambers 26 also provide a space in which a supply of sacks filled with the nuts or other material may be kept and preserved from the air and protected from the dust. Those plates 24 at the ends of the cabinet preferably will have notches 27 therein to fit the upright standards or posts at the rear of the case. The case may be made in various sizes and when the nuts, candy, or other articles are deposited therein, the material will be exposed to view on all sides and may be carefully examined in detail by a prospective purchaser.

I claim as my invention:

1. A show-case comprising a base, upright transparent side and end walls mounted thereon, corner braces fitting the angle of the side and end walls for securing them together, a cover or top plate resting upon said walls, depending hooks supported by the forward under portion of said cover, each having a horizontal foot adapted to slide under the lower edge of a corner brace to prevent the forward portion of said cover from being lifted, but adapting the rear side of said cover to be raised and moved

horizontally to disengage said feet from said braces.

2. A show-case comprising a base and transparent vertical walls, means for permitting said walls to be quickly removed from the base, transparent partitions dividing the case into vertical compartments, an inclined plate for each compartment, each plate having an opening in its lower end, and being positioned in the compartment to divide the same into an upper chamber and a lower chamber, each plate being loosely supported and having its lower end abutting the front wall and base, and having its upper end resting against the rear wall of the case.

3. A show-case comprising a base and transparent vertical walls, transparent partitions dividing the case into vertical compartments, an inclined plate for each compartment, each plate having an opening in its lower end, and being positioned in the compartment to divide the same into an upper chamber and a lower chamber, each plate being loosely supported and having its lower end abutting the front wall and base, and having its upper end resting against the rear wall of the case.

4. A show-case comprising a base and transparent vertical walls, an inclined plate having an opening in the lower end thereof, said plate positioned in the case to divide the same into an upper chamber and a lower chamber, said plate being loosely supported and having its lower end abutting the front wall and base portion and having its upper end resting against the rear wall.

In witness whereof, I have hereunto set my hand this 16th day of January, 1925.

JAMES CLIFFORD JOHNSON.
